R. L. WILCOX,
METHOD FOR POINTING AND THREADING SCREWS, BOLTS, AND SIMILAR ARTICLES,
APPLICATION FILED JULY 21, 1916.

1,253,323.

Patented Jan. 15, 1918.

UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

METHOD FOR POINTING AND THREADING SCREWS, BOLTS, AND SIMILAR ARTICLES.

1,253,323.

Specification of Letters Patent. Patented Jan. 15, 1918.

Original application filed August 23, 1915, Serial No. 46,941. Divided and this application filed July 21, 1916. Serial No. 110,518.

To all whom it may concern:

Be it known that I, RICHARD LESTER WILCOX, a citizen of the United States, residing at Waterbury, in the county of New Haven 5 and State of Connecticut, have invented a certain new and Improved Method for Pointing and Threading Screws, Bolts, and Similar Articles, of which the following is a specification, reference being had therein 10 to the accompanying drawings.

My invention relates to a new and improved method for pointing and threading screws, bolts and similar articles, preferably with dies that may be economically constructed, be interchangeable, reversible, and attachable to any one of the many forms of thread rolling machines now in common use.

To these, and other ends, my invention consists in the method for pointing and 15 threading screws, bolts and similar articles, substantially as hereinafter described and illustrated in the accompanying drawing, wherein,—

Figure 1 is a plan view of a pair of thread 20 rolling dies by which my invention may be practised and occupying the relative positions assumed by them at the commencement of the thread rolling operation;

Fig. 2 is a perspective view of one of the 25 dies;

Fig. 3 is a face view thereof with the knife plate removed;

Fig. 4 is an end view thereof;

Fig. 5 is a face view of the knife plate;

Fig. 6 is an edge view thereof;

Fig. 7 is an end view thereof; and

Figs. 8, 9, 10, 11 and 12 are enlarged sectional views of the die and knife plate, taken 30 respectively upon lines A, B, C, D and E of Fig. 3, with the blank shown in connection therewith.

Heretofore it has been the practice to produce a gimlet point screw by pointing the blank in a lathe, shaving machine or similar 45 mechanism, and afterward forming a thread thereon or by rolling a V groove in the shank of a blank having a head at both ends thereof, and then threading the walls of said V groove which thereby become the pointed 50 ends of two bolts or screws, after which, that portion of the shank between the V groove and heads is threaded, but in my improved method the blanks having a head

at only one end thereof are both pointed and threaded at one and the same time.

One form of means for practising my improved process is shown in the drawings, wherein the numeral 1 designates the fixed die and 2 the movable die, both being of substantially the same shape, differing only 55 in their length, the fixed die being shorter than the movable die, and the former being provided with the guide notch 9. These dies are secured in the usual way in any one of the many common forms of thread rolling 60 machines. Each die has an angular recess 3 in one side thereof and upon the adjacent faces are the knives 4, which are parallel with the side of the dies and terminate at their inner ends at the edge of the recess 3. 65 The front face of each of the dies is provided with the usual thread rolling grooves 5 which extend from the outer edges of the dies to and upon one side of the knives 4 (see Fig. 2).

Secured within the recess 3 by a screw 6 is the knife plate 7, having the knives 8 at opposite ends and upon opposite sides thereof. The knife plate 7 is so shaped and designed that its position within the recess 3 70 may be reversed end for end, if desired.

The dies 1 and 2 are arranged relatively so that each of the knives 8 upon the knife plate 7 is in the same line as one of the knives 4 upon the opposite die and the ends 75 thereof have substantial contact with each other.

In practice, the blank, designated herein by the numeral 10, is placed between the dies in the usual manner, its starting position 80 being substantially shown in Fig. 8, and its alinement being determined by the guide notch 9. As the movable die 1 advances parallel with the face of the fixed die 2, the thread is rolled upon the shank of the blank 85 and the knives 4 and 8 force their edges into the blank until a small portion of the end of the blank, designated herein by the numeral 11, is separated from the blank and drops from between the dies into a receptacle conveniently arranged to receive it and 90 leaving the end of the blank pointed, substantially as shown in Fig. 11.

The successive steps required to produce this result are shown in Figs. 9, 10 and 11, 105 and the further movement of the movable

die advances the blank so that the tapered or gimlet point end is threaded by the grooves 5, which are formed in the outer curved face of the knives 4, as above described, thus completing the screw.

With this method of pointing and threading screws only the minimum amount of material is wasted, and at least one complete operation, necessary in the old practice, is eliminated.

In minor details the means adopted to accomplish my new and improved method may be altered, and I do not therefore limit myself to the detail mechanism as shown and described, except as the scope of the claims requires.

Having described my invention, what I claim as new and desire to secure by Letters Patent, is:—

1. The process of providing a pointed article having a continuous thread of uniform pitch thereon consisting in threading the

blank and simultaneously pointing the end and finally completing the thread of the blank on the end in a continuous operation. 25

2. The process of pointing the blank and rolling a thread of uniform pitch thereon at one and the same time, said pointing process cutting off a portion of one end of the blank during the threading operation and the 30 thread on the shank and point being of uniform pitch for process, the pointing the blank and rolling a thread thereon consisting in rolling a thread upon the shank of the blank beyond the point and pointing the 35 blank simultaneously therewith, and in a continuous operation completing the threading of the pointed portion in continuation of and having uniform pitch with the thread on the shank. 40

In testimony whereof I have hereunto affixed my signature.

RICHARD LESTER WILCOX.
